UNITED STATES PATENT OFFICE.

JOHN WRIGHT, OF HOOSICK FALLS, NEW YORK.

DESIGN FOR A GAS-BRACKET.

SPECIFICATION forming part of Design No. 17,863, dated November 1, 1887.

Application filed August 11, 1887. Serial No. 246,742. Term of patent 14 years.

To all whom it may concern:

Be it known that I, JOHN WRIGHT, a citizen of the United States, residing at Hoosick Falls, in the county of Rensselaer, State of New York, 5 have invented a certain new and original Design for Gas-Brackets, of which the following is a specification, reference being had therein to the accompanying drawing.

In the drawing is represented a perspective 10 of my newly-designed gas-bracket, this view being deemed necessary to fully illustrate the same; and it consists of the curved and gradually-tapered body A, it being a conventional representation of an animal-horn provided

with an ornamental tip, B, and the annular 15 beaded tapered base having the tubular pipe C.

I claim—

The design for gas-brackets herein described, 20 the same consisting of the curved and gradually-tapered body A, provided with an ornamental tip, B, and the annular beaded tapered base having the tubular pipe C.

In testimony whereof I affix my signature in presence of two witnesses.

JOHN WRIGHT.
